(57) **CLAIM**

(22) Filed: **Sep. 2, 2013**

I claim the ornamental design for an infant recreational floatation device, as shown and described.

(51) **LOC (10) Cl. 21-06**

DESCRIPTION

(52) **U.S. Cl.**

FIG. 1 is a perspective view of an infant recreational floatation device in accordance with an embodiment of our design.

USPC **D21/803**

FIG. 2 is an end view of the infant recreational floatation device shown in FIG. 1.

(58) **Field of Classification Search**

FIG. 3 is an opposite end view of the infant recreational floatation device shown in FIG. 1.

USPC D21/769-770, 801, 803, 809; 114/253,
114/345-346; 441/35, 66, 74, 40-42,
441/129-132; 472/128-129; D12/5, 6, 316;
D6/392, 595, 596, 601, 604, 605

FIG. 4 is a right side elevational view of the infant recreational floatation device shown in FIG. 1.

See application file for complete search history.

FIG. 5 is a left side elevational view of the infant recreational floatation device shown in FIG. 1.

(56) **References Cited**

FIG. 6 is a top plan view of the infant recreational floatation device shown in FIG. 1; and,

U.S. PATENT DOCUMENTS

FIG. 7 is a bottom plan view of the infant recreational floatation device shown in FIG. 1.
